UNITED STATES PATENT OFFICE.

OTTO L. MERTZ, OF CHICAGO, ILLINOIS, ASSIGNOR TO JULES HERBERT BENJAMIN, OF CHICAGO, ILLINOIS.

BINDER FOR PACKAGE-TIES.

1,370,755.

Specification of Letters Patent.

Patented Mar. 8, 1921.

Application filed April 19, 1920. Serial No. 374,875.

To all whom it may concern:

Be it known that I, OTTO L. MERTZ, a citizen of the United States, and resident of Chicago, in the county of Cook and State 5 of Illinois, have invented certain new and useful Improvements in Binders for Package-Ties, of which the following is a specification.

My invention relates to means for dispensing and reissuing package ties. A modified 10 form of my construction is shown in a co-pending application, Serial No. 374,874, filed of even date herewith.

In the handling of small packages, particularly packages of letters by the Post 15 Office Department, it has been found desirable to employ a package tie which includes a metal member to which a string or cord of suitable length is secured, the tie being used 20 to facilitate the ready securing of the free end of the cord after it has been passed around the package. However, such ties should in the interest of economy be used repeatedly and it happens that in some offices 25 there will be a much larger receipt of package ties than are needed for outgoing mail resulting in a surplus which should be despatched to a central point and reissued to stations where the reverse condition 30 prevails; that is, where there is a demand for a greater number of package ties than is received. This result has been attempted to be accomplished heretofore by bundling or binding a quantity of the package ties but 35 in each instance it has been found that the ties, when so bundled, become entangled and inextricably mixed, thus rendering their reuse impossible.

The construction herein disclosed provides 40 for an improvement over that shown in my co-pending application referred to in that the spindle on which the ties are mounted is not reshipped with a bundle of ties; thus considerable weight is eliminated and there 45 is no likelihood of confusion due to shortage of spindles at any point.

The invention will be more readily understood by reference to the accompanying drawings, wherein,

50 Figure 1 is a perspective view of a dispensing and reissuing device constructed in accordance with my invention;

Fig. 2 is a view showing a bundle of ties, the spindle being indicated in dotted lines;

Fig. 3 is a plan view of the bundle shown 55 in Fig. 2, and

Fig. 4 is a perspective view of the clip which is associated with the spindle.

In the drawing it will be seen that the spindle is composed of a flat strip 10, having 60 longitudinal flanges 11, which serve to form a channel-shaped member on which the ties are mounted. A foot 12, is formed by bending the portion 10, at right angles, the foot being more or less permanently secured to a 65 table or support 13, by suitable means. At its upper end the web or body portion 10, is slotted as at 14, for a purpose later to be described. The ties which I prefer to employ consist of a flat body portion 15, each 70 having a struck-up tongue 16, around which the free end of the tying cord 17, is twisted in a well known manner. The cord engages the tie by means of an aperture and an offset portion 18, as best shown in Fig. 3. At its 75 opposite end the tie is provided with an elongated opening 19, so shaped as to permit it to engage with the spindle and to hold the ties in relatively fixed relation, thus avoiding the possibility of tangling of the 80 cords.

A clip, such as best shown in Fig. 4, comprises a flat strip 20, having a hooked portion or tongue 21, adapted to engage with the web 10, of the spindle, the flat portion 85 lying in a channel formed by the flanges 11 of the spindle. A cord 22, is secured to the clip, and as shown in Fig. 1, it preferably engages the slot 14 and depends in the channel of the spindle. The clip thus constitutes 90 no material obstruction to the insertion or removal of ties from the spindle. However, assuming that the spindle has become filled with ties and it is desired to ship a bundle thereof, the clip is disengaged from the free 95 end of the spindle and the cord 22, on which the ties are threaded, because of the position of the cord relative to the spindle, is engaged with the tongue 21 of the clip and the ties then removed vertically from the 100 spindle. A bundle of ties is thus formed which may be disposed of to a central point for reissue as desired. When received at a new point of use the ties may be mounted upon a similarly shaped spindle if desired 105 and used as required.

I claim:

1. In means of the class described, the

- combination of a relatively fixed spindle, a clip engaging the free end thereof, a cord secured to the clip and adapted to extend downwardly in parallelism with the spindle, the spindle and cord being adapted to receive a plurality of package ties, the cord being then adapted to engage said clip upon its removal from the spindle in order to bind the package ties in a bundle.
- 5 2. In a package tie reissuing device, the combination of a spindle, a clip engaging the free end of the spindle, the clip having a depending cord adapted to engage the opening in package ties received by said spindle, said clip being adapted to be vertically removed from the spindle together with the ties and to serve as means of attachment for the free end of said cord in order to bind the package ties in a bundle.
- 10 3. A package tie reissuing device, comprising the combination with a relatively fixed spindle, of a clip adapted to vertically engage the free end of the spindle, a cord secured to the clip and adapted to lie along- 25 side of the spindle, the spindle and cord being adapted to receive a plurality of package ties, the clip being adapted to be vertically removed from the spindle with the ties mounted thereon, the free end of the 30 cord with the ties mounted thereon being held by engagement with the portion of the

clip which had been in engagement with the spindle.

4. In package tie reissuing means, the combination of a spindle having a flat body 35 portion provided with a slot at its upper end, a flat clip having a hooked end adapted to engage with the body portion of the spindle at its upper end, a cord secured to the clip and adapted to lie in the slot in the spindle, 40 the spindle being adapted to receive package ties having openings of a shape corresponding substantially to that of the spindle, a plurality of ties engaging the spindle and the cord and being adapted to be removed from the spindle and be held by the cord, the free end of the cord engaging the hook portion of the clip.

5. In means of the class described, the combination of a spindle of channel shape in 50 cross-section, a clip in the form of a flat strip having a hooked end, the clip being adapted to be mounted on the free end of the spindle with its flat portion in the channel of the spindle, and a cord secured to the 55 clip and adapted to be employed to secure package ties in a bundle.

Signed at Chicago, Illinois, this 15th day of March, 1920.

OTTO L. MERTZ.
